UNITED STATES PATENT OFFICE.

ALBERT J. DREHER, OF CINCINNATI, OHIO, ASSIGNOR TO THE AMERICAN LAUNDRY MACHINERY COMPANY, OF CINCINNATI, OHIO, A CORPORATION OF OHIO.

CLAMPING CLIP FOR NECKBAND EXPANDERS.

Application filed February 1, 1922. Serial No. 533,349.

This invention relates to improvements in neckband expanders used in connection with the ironing of shirts and more particularly the type used to expand the neckbands of shirts having collars attached.

The objects of this invention are to provide a neckband expander with an improved clamping clip together with means for locking the clip in clamping position; and more specifically to provide a locking means which has pivotal and sliding movement for releasably locking the clip in clamped position.

Other objects of the invention will be apparent from the following description and claims when considered together with the accompanying drawings.

Fig. 1 is a vertical longitudinal section of an ironing board embodying my improved device; Fig. 2 is a transverse section taken on line 2—2, Fig. 1; Fig. 3 is a sectional view similar to Fig. 1 showing part of the device with clamping clip in raised position; Fig. 4 is a view similar to Fig. 3 with the clamping clip in lowered position; Fig. 5 is a plan view of the neckband expander; Fig. 6 is a horizontal section of the neckband expander taken through the plane of line 6—6, Fig. 2; Fig. 7 is a section taken through the plane of line 7—7, Figs. 2 and 5 showing the lock in detail; and Fig. 8 is a section taken through the plane of line 8—8, Figs. 2 and 5 showing the other side of the lock in detail.

The guide 1 is suitably mounted upon the main table or support 2 and is provided with the bracket 3 for support of the guide plate 4 for the neckband former. The ironing table 5 is mounted upon the support 6 which has sliding movement upon the main support 2. The main stationary portion of the neckband former is indicated at 7 while the rear portions 7' are adapted for adjustable movement according to the shape and size of the neckband of the shirt. The adjustable extension blocks 7' have sliding movement in one direction by means of their guide pins 8 engaging the main stationary part of the neckband former and in the other direction along the guide pin 9 which extends through the top portion of the yoke plate 10 and is secured thereto by means of the set screw 11. The mechanism for operating the yoke ironing member 10^a forms no part of the present invention. The pins

12 extend through the guides 13 and through the stationary portions 7 of the neckband expander whereby it is possible for the neckband expander to yield downwardly as may be necessary during the ironing operation, the upper rear portions of the ironing table 5 being cut down as indicated at 5^a to permit such depression of the neckband expander during the ironing operation. The springs 12^a are provided for the pins 12, these springs having abutment against the guide plate 4 and the main part of the neckband expander. The pins 12 extend also through the brackets 15 secured to the underside of the guide plate 4. Slidably mounted upon the main part of the neckband expander there is provided the bracket 17 which has the ribs 18 engaging in the slots 19. The bracket 7^a on the main part 7 of the neckband former has a projection surrounded by spring 17^a, the other end of which abuts the bracket 17.

Pivottally mounted at the point 20 upon the slide bracket 17 is the clamping clip 21 which is adapted to be lowered for clamping engagement with the front portion of the neckband of the shirt. The locking member 22 is provided with a slot 23 for slidable engagement with the flat faces of the guide pin 25 and of the pivot pin 20, the guide pin 25 being mounted upon the bracket 17. The slot 23 terminates in an enlarged and circular opening 27 which is adapted to receive the pivot pin 20 upon proper sliding adjustment of the lock 22. When adjusted to such position it is possible to rotate the clip 21 about its pivot. Then when the clip 21 has been lowered to clamping engagement with the neckband of the shirt the clip can be locked in such position by slidable adjustment of the locking member 22 so as to have the slot 23 engage the flat faces of the pivot 20, thereby preventing raising of the clip 21.

The guide pin 28, which extends through the expander 7, is connected at its one end with the screw 29 secured in the sliding bracket 17, while the other end of the pin 28 extends through the opening 30 in the yoke plate 10. The pin 28 extends also through the depending arm of the guide pin lock 31 which is provided with the button 32 for manipulation thereof. The lower end of the lock 31 engages in the recess 32' formed in the slide 33 which is mounted in

the neckband former. The guide pin 28 is provided with a shoulder 34 for engagement by the opening in the lock member 31, that is, upon sliding adjustment of the bracket 5 17 after the clip 21 has been lowered to engage the neckband of the shirt. The spring 35 tends to hold the lock 31 in engagement with the shoulder 34. The stop collar 36 which is mounted in the neckband expander 10 is adapted to be engaged by the stop point of the screw 29 and also by the stop screw 37 which is provided upon the slide 33.

The slide 33 is adjusted by means of the bell crank lever 38, the upper end of which 15 has pivotal connection with the slide 33 at the point 39. The pin 40 carried by the bell crank lever 38 engages the vertical grooves 41 formed in the sides of the depending brackets 15, thereby providing a pivot point 20 for the bell crank lever. The lower end of the lever 38 has pivotal connection at 43 with the shackle 44 carried by one end of the rod 45. The rod 45 carries a swivel block 46 which can be slid thereon against 25 the tension of spring 47 whose other end abuts against the nuts 48 carried by the rod 45. The collar 49 on the rod 45 limits the movement of the swivel block in the other direction. The arm 50 of the bell 30 crank lever 51 has pivotal connection with the swivel block 46 and is provided with the rollers 52 which are adapted for engagement by the cam 53 which is mounted upon the shaft 54 and can be operated by 35 the lever arm 55. The segmental gear 56 which is also mounted upon the shaft 54 has meshing engagement with the companion segmental gear 57 mounted upon the shaft 58 which carries also the arm 59 with the 40 roller 60 for engagement with the sliding support 6.

After dressing the shirt upon the ironing board, the clip 21 is lowered so as to engage the neckband, the lock 22 having 45 been adjusted to permit pivotal movement of the clip. The locking member 22 is then slid into locking position so as to prevent raising movement of the clip, and the bracket 17 is slidably adjusted against the tension of spring 17^a so as to cause the shoulder 34 to be engaged by the edge of the opening through the arm of the locking lever 31, the spring 35 tending to hold the lever 31 in such engagement. This movement of 50 the sliding bracket 17 tends to further clamp the clip 21 in engagement with the front portion of the neckband. Then upon raising the lever 55, the cam 53 will engage one of the rollers 52 so as to cause rocking 55 movement of the bell crank lever 51 and movement of the arm 50 to the right as viewed in Fig. 1. The spring 47 is thereby placed under tension and the rod 45 is moved to the right, causing the slide 33 to 60 move to the left, as viewed in Fig. 3. By 65

virtue of the engagement of the lever 31 in the notch 32^a together with the engagement of the lever 31 with the shoulder 34, the movement of slide 33 causes firm clamping action of the clip 21. This action takes 70 place prior to the engagement of the roller 60 with the sliding support 6. Further operation of lever 55 will, through gears 56 and 57, cause engagement of roller 60 with support 6 so as to move the ironing table 75 and yoke plates to the left as viewed in Figs. 1 and 3. At the same time the rear portions of the neckband former are extended according to the size and shape of the neckband which is thereby placed under tension. The shirt is then in condition 80 for the ironing operation.

Upon completion of the ironing operation, the lever 55 is lowered so as to cause the roller 60 to engage the web to return the support 6 to the position shown in Fig. 1, and to relieve the tension on the neckband of the shirt. Depression of the button 32 will release the engagement between the lever 31 and the shoulder 34, whereupon the spring 17^a will force the sliding bracket 17 to the right, as viewed in Fig. 3, thereby relieving the clamping action of the clip 21. Then upon sliding adjustment of the locking member 22, so as to bring the end portion 27 of the slot to surround the pivot pin 20, the clip 21 can be raised so as to altogether release the neckband of the shirt.

Since the ironing board has an angular pitch, as illustrated in the drawings, it is possible to employ my present invention to iron a shirt having an attached collar as well as the ordinary shirt without the collar; since, upon applying tension to the neckband, the attached collar is caused to lie on the angular surface and will not be damaged by the engagement of the ironing chest. The operation is the same in the two cases.

What I claim is:

1. In combination, a neckband former, a support movable inwardly and outwardly relative thereto, a clamping device movably connected to said support for movement into and out of registering position opposite the front of a neckband on said former, means for locking said device in said registering position to said support, yielding means opposing inward movement of said support toward the center of said former, and means arranged to hold the support when moved to its inner position.

2. In combination, a neckband former, a support movable inwardly and outwardly relative thereto, a clamping device pivotally connected to said support for movement into and out of registering position opposite the front of a neckband on said former, means for locking said device in said registering position to said support, means ar-

ranged to hold the support when moved to its inner position, and operating means for moving the support and thereby the device to produce clamping pressure thereof on a 5 neckband mounted in the former.

3. In combination, a neckband former, a support movable inwardly and outwardly relative thereto, a clamping device pivotally connected to said support for movement 10 into and out of registering position opposite the front of a neckband on said former, means for locking said device in said registering position to said support, yielding means opposing movement of said support 15 towards the center of said former, means arranged to hold the support when moved to its inner position and operating means for moving the support and thereby the device to produce clamping pressure thereof 20 on a neckband.

4. In combination, a neckband former in-

cluding relatively adjustable parts, operating means for adjusting the same, a support connected to said operating means, and movable towards the center of said former 25 when the former is expanded, a neckband clamping device movably connected to said support for movement into and out of registering position opposite the front of the neckband former, and means for locking 30 said device in its said registering position.

5. In combination, a neckband former, a pivoted clip for clamping the front portion of the neckband against said former, said clip having a pivotal pin with a flat side, 35 and a slotted member having slidable engagement with said pivotal pin and having an enlarged portion in its slot to permit pivotal movement of said clip.

In testimony whereof I hereby affix my 40 signature.

ALBERT J. DREHER.
